CLAIM

The ornamental design for a dog chew toy, as shown and described.

DESCRIPTION

FIG. 1 is a perspective view of the dog chew toy of the present disclosure.

FIG. 2 is a front view of the dog chew toy of the present disclosure.

FIG. 3 is a rear view of the dog chew toy of the present disclosure.

FIG. 4 is a right side view of the dog chew toy of the present disclosure.

FIG. 5 is a left side view of the dog chew toy of the present disclosure.

FIG. 6 is a top plan view of the dog chew toy of the present disclosure; and,

FIG. 7 is a bottom plan view of the dog chew toy of the present disclosure.

The broken lines are for illustrative purposes only and form no part of the claimed design.

1 Claim, 6 Drawing Sheets
